UNITED STATES PATENT OFFICE.

WILLIAM H. PERRY, OF SAN DIEGO, CALIFORNIA.

DRYING APPARATUS.

Application filed May 10, 1920. Serial No. 380,073.

To all whom it may concern:

Be it known that I, WILLIAM H. PERRY, a citizen of the United States, residing at San Diego, in the county of San Diego and State 5 of California, have invented certain new and useful Improvements in Drying Apparatus, of which the following is a specification.

My invention relates to a drying apparatus more particularly adapted for drying fish, fruit or vegetables by evaporation, more particularly by the use of a current of warm air for removing the natural moisture from said fish, fruit, vegetables or other articles 15 and the objects of my invention are: first, to provide an apparatus in which a current of air is circulated continuously through a fan and through a circuitous air duct containing a conveyor for the article to be dried and in 20 which the moisture laden air is discharged at intervals as it passes along said conveyor laden with the article to be dried; second, to provide an apparatus of this class in which the air passing through and over the article 25 to be dried will as soon as it becomes sufficiently laden with moisture pass out and down through spaced apart apertures and the warm dry air pass to the intake of the fan and through said fan and out again for 30 use; third, to provide an apparatus of this class whereby the articles to be dried may be placed on the conveyor at one end and removed from the conveyor at the opposite end and dried in its movement through the air 35 duct through which the air passes in its circulations through the fan; fourth, to provide a new and novelly contructed drying apparatus for de-hydrating fruits, vegetables, fish and the like; fifth, to provide an apparatus of this class which is very simple and economical of construction and operation, very efficient in its action and which will not readily deteriorate or get out of order.

With these and other objects in view as 45 will appear hereinafter my invention consists of certain novel features of construction, combination and arrangement of parts and portions as will be hereinafter described in detail and particularly set forth 50 in the appended claims reference being had to the accompanying drawings and to the characters of reference thereon which form a part of this application in which:

Figure 1 is a longitudinal sectional view 55 through 1-1 of Fig. 2; Fig. 2 is a top or plan view of the apparatus showing portions

broken away and in section to facilitate the illustration; Fig. 3 is a sectional view through 3-3 of Fig. 1 and Fig. 4 is a sectional view through 4-4 of Fig. 1. 60

Similar characters of reference refer to similar parts and portions throughout the several views of the drawings.

The casing 1, partition 2, heating pipes 3, fan 4, conveyor 5, sheave 6, support 7, 65 support 8, sheave 9, and change speed transmission 10 constitute the principal parts and portions of my drying apparatus.

The casing 1 is practically an air tight casing provided with a partition 2 separating it into two air ducts A and B forming a continuous circuitous air passage. Mounted in the one end of this casing 1 is a fan 4, the casing being shaped to conform to the fan blades. The outlet of said fan communicates with the air duct A which is the outgoing air duct. The inlet of said fan communicates with one of the ends of the air duct B which is the incoming air duct so that the air circulates from the outlet of the 80 fan 4 through the air duct A around the end of partition 2 and back through the air duct B to the intake at the side of the fan. Mounted in these two air ducts A and B are pipes 3 which are heat conductors for either 85 steam or air which are adapted to connect with any air or steam suply so that the steam or air will circulate through these pipes for heating the air from the fan in its passage through the ducts A and B. Mounted longitudinally in the duct B and adapted to operate therein is the one side of a continuous formaminous conveyor 5 which passes through the casing 1 at opposite ends of the duct B through apertures 1^a and 1^b. The 90 aperture 1^b is provided with a slide door 1^c adapted to regulate the size of the aperture 1^b for regulating the quantity of air admitted from the outside to the fan inlet. In the lower side of the casing 1 below the air duct B are a plurality of apertures 1^d which are adapted to permit the exit of moisture laden air from the duct B when it becomes sufficiently laden so that it will pass down through these apertures 1^d as the air passes 105 toward the inlet of the fan 4. The conveyor 5 is provided with any change speed mechanism for changing the speed of conveyor, the particular change speed mechanism being no part of my present invention.

The operation of the dryer is as follows: The articles to be dried are placed on the

upper side of the foraminous conveyor outside of the casing and passed through the incoming air duct B on said conveyor preferably in the same direction as the air moves 5 and it is intended that the conveyor should be regulated to travel at the proper speed so that the articles on the conveyor are dried in their passage through the ducts B so they may be removed at the other end of said 10 duct after it passes out through the aperture 1^b. The air circulates continuously from the outlet of the fan over the heat pipes 3 around the end of the partition 2 and back through the air duct B to the inlet of 15 the fan. As a portion of the air becomes laden with moisture from the articles to be dried it passes down through the apertures 1^a and to the outside and the aperture 1^b is regulated to provide for the loss of the 20 moisture laden air which passes out through said apertures 1^a, thus the heated air is circulated continuously through the fan and released when the specific gravity becomes sufficient by reason of its becoming moisture laden to pass through said apertures. 25

Though I have shown and described a particular construction, combination and arrangement of parts and portions I do not wish to be limited to this particular construction, combination and arrangement but desire to include in the purview of my invention the construction, combination and arrangement substantially as set forth in the appended claims. 30

It is obvious that with this construction there is provided a drying apparatus in which heated air is circulated continuously over one side of a foraminous conveyor laden with articles to be dried that as soon 35 as any portion becomes sufficiently laden with moisture it passes outwardly through the apertures 1^a to the outside, the supply being kept up near the entrance of the fan through the aperture 1^b and that the air 40 inlet may be regulated so that the amount of moisture in the air eliminated through the apertures may be regulated dependent upon the quantity of natural moisture in the articles to be dried. 45

Having thus described my invention what I claim as new and desire to secure by Letters Patent is:

1. A drying apparatus including a casing provided with an outgoing and an incoming air duct and with a plurality of outlet apertures in its lower side and a forami-

nous conveyor with one side positioned in one of said air ducts and above said apertures.

2. A drying apparatus, including a casing 60 provided with a circuitous air duct, a foraminous conveyor with one side positioned in said air duct, the bottom of said casing having a plurality of outlet apertures in the lower side of said air duct below said conveyor and a fan with its outlet communicating with the outgoing portion of said air duct and its inlet communicating with the incoming portion of said air duct. 65

3. A drying apparatus, including a casing 70 provided with an outgoing and incoming air duct, a foraminous conveyor with one side positioned in said incoming air duct, the bottom of said casing having a plurality of outlet apertures in the lower 75 side of said casing below said conveyor, a fan with its outlet communicating with the outgoing air duct and its inlet communicating with the incoming air duct and means for admitting air into said casing from the 80 outside to the intake of said fan in regulated quantities. 85

4. A drying apparatus, including a casing 90 provided with an outgoing and incoming air duct, a foraminous conveyor with one side positioned in said air duct, the bottom of said casing having a plurality of air outlet apertures in said casing contiguous to said conveyor, a fan with its outlet communicating with the outgoing air duct and 95 its inlet communicating with the incoming air duct and means for regulating the speed of said conveyor.

5. A drying apparatus, including a casing 95 provided with an outgoing and incoming air duct, a foraminous conveyor with one side positioned in said air duct, the bottom of said casing having a plurality of outlet apertures in the lower side of said casing below said conveyor, a fan with its outlet 100 communicating with the outgoing air duct and its inlet communicating with the incoming air duct, means for admitting air into said casing from the outside to the intake of said fan in regulated quantities and 105 means for regulating the speed of said conveyor.

In testimony whereof, I have hereunto set my hand at San Diego, California, this 1st day of May, 1920.

WILLIAM H. PERRY.
